[57] **CLAIM**

The ornamental design for a portable flood control vacuum cleaning machine, as shown and described.

DESCRIPTION

FIG. 1 is a front perspective view of a portable flood control vacuum cleaning machine showing my new design;

FIG. 2 is a top plan view thereof;

FIG. 3 is a side elevational view thereof;

FIG. 4 is a rear perspective view thereof; and,

FIG. 5 is a side elevational view of the opposite side of FIG. 3.

The hoses are shown broken away in FIGS. 4 and 5 for ease of illustration and are fully disclosed in FIGS. 1-3.

FIG. 1

FIG. 2

FIG. 3

FIG. 4

FIG. 5
